UNITED STATES PATENT OFFICE.

WILLIAM M. HABIRSHAW, OF NEW YORK, N. Y.

ELECTRIC CABLE.

SPECIFICATION forming part of Letters Patent No. 661,244, dated November 6, 1900.

Application filed September 26, 1900. Serial No. 31,148. (No model.)

To all whom it may concern:

Be it known that I, WILLIAM M. HABIRSHAW, a citizen of the United States, residing at New York city, in the county and State of New York, have invented certain new and useful Improvements in Electric Cables, of which the following is a full, true, and accurate description, reference being had to the accompanying drawing.

10 The object of the invention which forms the subject of this application for Letters Patent is to produce a cable especially adapted for use in systems of electrical transmission involving the use of multiple circuits, especially those which are now commonly known as "three-wire-transmission" circuits for alternating currents. Such a cable to be durable and effective for the special purposes intended requires properties not heretofore essential in ordinary cables for conveying single currents, whether continuous or alternating, or the currents of several independent circuits.

15 I have devised a form of cable which is well adapted for the purpose above specified in that it is capable of conveying currents of great strength, and it is reduced in size to the smallest possible degree without impairing its insulating properties. In such a cable it is important that the strands shall be thoroughly insulated one from the other in order to avoid induction in case currents of different potentials are used in the several conductors of the same cable. It is essential also in a cable designed, as this one is, to carry heavy currents of electricity that the whole cable be very thoroughly insulated to prevent the grounding of the current. For this purpose a material of very high insulating qualities must be used.

20 The accompanying drawing represents a cross-section of my improved cable, A indicating a conductor, B a paper covering upon A, C a filling of jute, D a coating of vul-

canizable rubber or the like, and E an outside covering of braided or woven material.

25 The cable consists of a plurality of conductors, each of which is preferably composed of a number of strands of comparatively fine wire, each of said conductors being surrounded by a covering of paper. The paper-covered conductors are assembled in a group, either parallel or twisted, together with a filling of jute fiber, giving the whole a cylindrical form. Over this I then apply a layer 55 or coating of vulcanizable substance—such as india-rubber—and wrap or inclose the latter with a covering of braided cord or tape.

30 The paper covering of the conductors is or may be applied by any of the methods now 60 practiced in the art of insulating conductors by paper, and as an additional protection the paper itself may be saturated with an insulating compound or coated with the same. The jute filling may also be saturated or 65 coated with a suitable insulating solution.

35 What I claim as my invention is—

1. An insulated cable composed of a plurality of electric conductors, each inclosed in a coating of paper, laid together with a jute 7c filling, and a coating or layer of vulcanizable rubber surrounding the jute filling, the whole being taped and braided, substantially as set forth.

2. A multiple-strand cable, consisting of 75 one or more electric conductors, each inclosed in a paper covering, laid down in a bed of fibrous material, the whole being surrounded by a layer of vulcanizable rubber, as set forth.

3. A multiple-strand cable composed of 80 electric conductors inclosed in paper coatings and embedded in a filling of jute, a coating of vulcanizable rubber and an outside jacket of braided tape or twine, as set forth.

WILLIAM M. HABIRSHAW.
